J. G. BAUMANN.
SAFETY HOOK FOR GLAZING MACHINES.
APPLICATION FILED MAY 8, 1918.

1,392,041.

Patented Sept. 27, 1921.

FIG. 1.

FIG. 2.

UNITED STATES PATENT OFFICE.

JOSEPH G. BAUMANN, OF PHILADELPHIA, PENNSYLVANIA, ASSIGNOR TO ALFRED C. LAYMAN, OF WILMINGTON, DELAWARE.

SAFETY-HOOK FOR GLAZING-MACHINES.

1,392,041.

Specification of Letters Patent. Patented Sept. 27, 1921.

Application filed May 8, 1918 Serial No. 233,365.

To all whom it may concern:

Be it known that I, JOSEPH G. BAUMANN, a citizen of the United States, residing at 2236 E. Allegheny Av., Philadelphia, in the 5 county of Philadelphia, and State of Pennsylvania, have invented a certain new and useful Safety-Hook for Glazing-Machines, of which the following is a specification.

My invention relates to glazing machines 10 for leather finishing and has to do primarily with the bearings by which the rod support of a glazing tool is pivoted.

The purpose of my invention is to transfer the wearing surface of the bearing from 15 the rod or support to the pin and socket or other suitable bearing in which the pin does not rotate within the rod.

A further purpose of my invention is to provide a bearing for the rocker-head in 20 which the supporting hooks are fixed with respect to the pin of the bearing and oscillatory movement takes place between the pin and the supports therefor.

Further purposes will appear in the specification and in the claims hereof.

I have preferred to illustrate my invention by but one form thereof, selecting as this preferred form a construction which has proved in use to be practical, efficient 30 and inexpensive and which at the same time well illustrates the principles of my invention.

Figure 1 is a vertical longitudinal section corresponding in position to line 1—1 35 of Fig. 2, showing my preferred form.

Fig. 2 is a rear elevation of the construction seen in Fig. 1.

Figs. 3 and 4 are enlarged fragmentary sections at right angles to each other corresponding to the construction in Figs. 1 40 and 2 and in the positions shown by lines 3—3 in Fig. 4 and 4—4 in Fig. 3.

In the drawings, similar numerals indicate like parts.

45 In glazing machines, such for example as the Bower machine, a great deal of difficulty has been found in supporting the rocker-head suitably to permit proper movement, while maintaining the strength of the support. The moving parts have a large momentum and move so rapidly that the wear upon the supporting rods is large and the rods themselves frequently break, constituting a danger to the operators and causing 50 injury to the machinery.

In the drawing I have shown the usual base 1, vertical standards 2, 2', top bar 3 and cross frame 4. The bed 5 is provided with a pad 6 upon which the leather is to be treated.

60 The cross frame lies between the standards and comprises transversely extending main cross pieces 7 and 8 supported at their ends and on opposite sides of the central space 9. The lower faces at the sides of the frame form a guiding contour 10, termed a track against which bears the curved upper surface 11 of rocker-head 12. This track defines the path of movement of the rocker-head and of the depending bracket 13 rigidly secured thereto.

65 The rocker-head is anchored against longitudinal movement by a rod 14 secured to the cross piece 7 as at 15 and to a pin through the rocker-head as at 16. Vertical movement of the rocker-head is controlled by a floating bar 17 and hooks 18—19 resiliently pressing the upper contour 11 against the track 10 in whatever angular 70 position the rocker-head occupies.

75 The resilience of the support is obtained by springs 20—21 between the cross pieces 7 and 8 and the floating bar 17. The springs are held against displacement by studs 22.

The rods 18 19 are fastened at their upper 85 ends to a bar 23 which has a curved surface and is free to oscillate in a recess 24 in bar 17; and at their lower ends are connected to the rocker-head by a pin 25.

The bracket 13 is held in position laterally 90 by guides 26, one on each side. It carries a head 27 pivoted at 28 and terminating in tool 29. This head is operated and the rocker-head is rocked by a connecting rod 30 rigidly secured to the head at 31 at one 95 end and to a wrist pin 32 upon operating wheel 33 at the other end.

As far as has been detailed this structure is old and well known, except for the type of connection used and the fact that the rods 18, 19 are rigid, where those previously used have been jointed in the middle by a hook joint. My invention has to do with the connection between the lower ends of hooks 18 and 19 and the rocker-head 12.

100 In the prior construction the pin extended across the rocker-head, passed through the bends at the lower ends of the hooks and turned in them, wearing the hooks and pin excessively, reducing their 110

strength and unduly increasing the friction at this point.

By my invention I secure the hooks to the transverse pin in such a way as to prevent 5 turning movement between them and provide the bearing between the ends of the pin and sockets or bearing parts formed in the rocker-head.

In order to most effectually and conveniently prevent turning of the pin 25 and the ends 34 of the hook members I bend the hook so as to make the two sides 35 and 36 approximately parallel and flatten the sides of the pin as at 37 and 38. Of 15 course any effective union at this point would prevent turning. The form shown has been selected as simple and convenient, inexpensive and easily placed and withdrawn.

20 I protect the parts from dust, provide for sufficient oiling and at the same time greatly improve the bearing quality by seating the ends of the pin in the cups 39, 40 which are provided with oil holes 41 and are tightly 25 held in position within the sides 42, 43 of the rocker-head by screws 44 passing through flanges 45.

I am thus able to use a steel pin within brass cup bearings greatly reducing the friction and wear and permitting quick and easy 30 replacement of the cup parts when appreciably worn.

It will be obvious that my invention may be used not only in the manufacture of the 35 new machines but that it may also be quickly and easily applied to the improvement of existing machines.

It will also be obvious that the parts, which for convenience I have called hooks, 40 need not be of hook-formation and if the form of hooks be used they need not be integral but can be divided as desired.

Having thus described my invention, what

I claim as new and desire to secure by Letters Patent is:—

45

1. In a glazing machine comprising a fixed track, a resilient support above the track, a rocker head below the track, rods depending from the support to hold the rocker head and a pin in the rocker head 50 with which the rods engage, the novelty which comprises rods and pin so formed as to prevent relative rotation between them and to provide cylindrical metallic bearings in the rocker head for the pin.

55

2. In a structure according to claim 1 the novelty which comprises rods terminating in hooks of non-circular contour and a pin conforming to said contour to prevent the rotation of the pin.

60

3. In a structure according to claim 1, the novelty which comprises bearings in the form of cups.

4. In a structure according to claim 2 the novelty which comprises bearings in 65 the form of cups.

5. In a structure according to claim 1, the novelty which comprises bearings having flanges by which they are secured in position in the rocker head.

70

6. In a structure according to claim 2, the novelty which comprises bearings having flanges by which they are secured in position in the rocker head.

7. In a structure according to claim 3, 75 the novelty which comprises bearings having flanges by which they are secured in position in the rocker head.

8. In a structure according to claim 4, the novelty which comprises bearings having flanges by which they are secured in 80 position in the rocker head.

JOSEPH G. BAUMANN.
